METHOD OF MAKING LAMP SOCKETS

William P. Tolbert, Fort Madison, Iowa, assignor
to Anthes Force Oiler Company, Fort Madison,
Iowa, a corporation of Iowa

Application April 27, 1942, Serial No. 440,635

2 Claims. (Cl. 113—116)

The present invention relates to the manufacture of lamp sockets and is particularly directed to an improved process of making that type of lamp socket which is commonly used in head lights and tail lights and similar installations in trucks and automobiles. These lamp sockets comprise a cup-shaped element having a reduced extension at the bottom of the cup, which extension is open at its end and is used as a means of mounting the cup. The extension, for example, may be passed through an aperture in a supporting structure and bent over and outwardly to clamp the cup in place. The electrical leads for the lamp pass out through the opening in the extension. The lamp unit itself is supported in the socket by means of bayonet slots oppositely disposed in the socket and pins on the lamp unit. Lamp sockets of this character are now drawn from metal and are quite satisfactory from the standpoint of operation.

The purpose of my invention is to provide a method of making a lamp socket which is fully satisfactory for the same purpose but which is produced at a substantial saving in time and material so that the ultimate cost of the socket is reduced by as much as one-half.

In the manufacture of the drawn socket the operations are generally as follows: a disc of metal is blanked out of the metal sheet and in connection with the blanking operation or as a separate operation it is drawn to a shallow cup. Then a second drawing operation and a trimming operation occurs wherein the full depth of the cup is attained and the open end of the cup is trimmed. Next the bayonet slots are pierced from the sides, each bayonet slot necessitating a separate operation. The reduced extension is then formed by a piercing and burring operation.

The manufacture of a socket in the fashion just described does not lend itself to a progressive operation. However, my method is of such nature that continuous progressive operation is the best way in which to make the socket.

Specifically it is the purpose of the present invention to provide a method of making a lamp socket wherein a strip of metal is embossed, pierced and burred, drawn and formed into a complete socket with a minimum amount of waste material and a minimum number of operations. I utilize the formation of the bayonet slots as a part of the preparation of the blank for drawing and forming so that the material which has to be taken out to form the bayonet slots is removed before there is a cup. I avoid any operations on the cup and thus prevent any

weakening or distortion of the formed cup. I make the size and shape of the removed piece such as to produce the proper dimensions of the blank with respect to the punch and die to obtain the optimum strength in the completed socket shell, as well as to produce a bayonet slot.

The features and advantages of the invention will appear more fully as the description proceeds, reference being had to the accompanying drawing wherein the preferred steps of the method are illustrated diagrammatically and the ultimate form of the finished article is shown. It is to be understood however that the drawing and description are illustrative only and are not to be taken as limiting the invention except insofar as it is limited by the claims.

In the drawing:

Fig. 1 is a somewhat diagrammatic plan view illustrating the progressive stages through which 20 a strip of material goes up to the point where the die is brought down over the blank and punch in the final drawing and forming operation which produces the cup-shaped socket;

Fig. 2 is a sectional view taken substantially 25 on the line 2—2 of Fig. 1, with punch and die elements also indicated;

Fig. 3 is a view in side elevation of the completed socket showing how it receives a standard lamp; and

Fig. 4 is a sectional view taken substantially 30 on the line 4—4 of Fig. 3 with the lamp removed.

Referring now in detail to the drawing, Fig. 1 shows in plan a strip of metal that has progressed far enough to have had performed thereon all of the operations excepting the severing and drawing and forming operation. The initial station in the production of the lamp socket is shown at the right in Fig. 1. This is the station where the material is embossed slightly as indicated at 10 as an initial step in forming the reduced extension of the ultimate cup-shaped socket. This operation is performed at the entering end of a strip of metal 9 which is the proper width to form a socket of the ultimate desired length. At the next station in a progressive operation the embossed portion 10 of the strip is increased in height. At the third station the embossed part 10 is pierced at 11 with a small opening, and the size of the opening 11 is such as to prevent the metal, when it is forced outwardly at the reduced extension, from splitting.

The strip is then fed forward to the fourth station where it is pierced to provide an opening 12. The material removed to form the openings 11 and 12 constitutes the material wasted for

each completed tube. It is necessary to form the opening 12 in order to form the bayonet slots, as will appear more fully hereinafter. At the fourth station the burring operation, by which a reduced extension 13 is formed from the embossed part 10, takes place.

In the fifth and final stage in the progressive operation a punch 14 is centered directly beneath the reduced extension 13 by a projection 14a that fits in the extension 13. The end of the strip is cut off along the lines 15 and 16 and the metal is drawn over the punch 14 by a die 17 and the ends of the cut off blank are formed into semi-cylindrical shape about the punch. Upon the opening movement of the press the finished article is discharged.

It will be seen from the foregoing description that a completed socket is formed for each operation of the press. A strip of metal is fed into one end of the press and the sockets are discharged at the other end.

I have discovered a definite relation which must be maintained between the width of the piece and the socket diameter in order to obtain the optimum strength and shape of the final cup. It will be noted from an inspection of the completed cup and an inspection of Fig. 1 that a certain portion of the metal (indicated at 18 in Fig. 1 by a dot and dash circular outline), substantially at the center of the piece, is drawn down over the punch to form a completely closed cup at the base of the socket. This width of metal which is drawn down over the punch acts to impart sufficient rigidity to the socket walls to prevent the natural recovery of the metal from spreading the open end of the socket enough to cause the socket to hold the lamp insecurely. It must not be of an amount sufficient to cause the metal to crowd or thicken up in the drawing operation because then the natural tendency of the crowded metal to expand when released from the die would increase the "bell" or recovery and furthermore weaken the structural strength of the cup. The piece for a standard size socket having a diameter of .640 inch should be .813 inch wide or approximately 1.27 times the socket diameter (the socket diameter being taken from center of metal to center of metal). In other words, the socket diameter is substantially four-fifths of the width of the cut off piece at the center line of the strip.

The socket formed by my method does "bell" or increase in size somewhat toward the open end. This permits a lamp to be inserted more easily and permits a limited amount of movement that tends to prevent the lodging and accumulation of corrosion products, dirt, etc. Electrical contact through the pins on the lamp and the hook portions of the bayonet slots is equally satisfactory with that in the drawn sockets.

It will be noted that the enlarged portion of each bayonet slot extends all the way up to the drawn part of the socket. This wide opening makes the positioning of the lamp to seat in the notches of the bayonet slot less critical. When the lamp is inserted far enough that the pins clear the points of the bayonet slots any further insertion makes no difference. The lamp can be turned even though it is pushed in way beyond normal position.

The notch or hook portions of the bayonet slots are spaced properly because the pilot projection 14a exactly centers the piece. Even a slight variation in the positioning of the notches does not prevent the lugs on the lamp from engaging in the notches because the slight "bell" of the cup permits adjustment of the lamp under the spring pressure that holds it in place.

From the foregoing description it is believed that the nature of the present invention and the best mode of carrying it out will be clear to those skilled in this art.

Having thus described my invention, what I claim as new and desire to secure by Letters Patent is:

1. A method of making a lamp socket, comprising taking a strip of metal and deforming and cutting it in progressive steps by drawing a relatively small tubular sleeve, then cutting out long narrow transverse pieces of the metal between the side edges of the strip and at a fixed distance from the small sleeve and cutting the strip transversely from the ends of the opening left by the cut out piece, and drawing and forming the generally rectangular piece thus cut off into a tubular socket wherein the cut edges along the sides of the piece define oppositely disposed bayonet slots, and an annular portion of the piece centered about said tubular sleeve is drawn into cylindrical shape.

2. A method of making a lamp socket, comprising taking a strip of metal and deforming and cutting it in progressive steps by drawing a relatively small tubular sleeve, then cutting out long narrow transverse pieces of the metal between the side edges of the strip and at a fixed distance from the small sleeve and cutting the strip transversely from the ends of the opening left by the cut out piece, and drawing and forming the generally rectangular piece thus cut off into a tubular socket of a diameter equal to substantially four-fifths of the width of the piece wherein the cut edges along the sides of the piece define oppositely disposed bayonet slots, and an annular portion of the piece centered about said tubular sleeve is drawn into cylindrical shape.

WILLIAM P. TOLBERT.
